D 163/5

UNITED STATES PATENT OFFICE.

R. PAUL HEMMING, OF PHILADELPHIA, PENNSYLVANIA, ASSIGNOR TO
GEORGE W. ENNIS & CO., OF SAME PLACE.

DESIGN FOR A CURTAIN.

SPECIFICATION forming part of Design No. 16,315, dated October 6, 1885.

Application filed August 31, 1885. Serial No. 175,850. Term of patent 3½ years.

To all whom it may concern:

Be it known that I, RICHARD PAUL HEMMING, a citizen of the United States, residing at Philadelphia, in the county of Philadelphia and State of Pennsylvania, have invented and produced a new and original Design for a Curtain; and I do hereby declare that the photographic print accompanying this specification conveys to any one skilled in the art a clear understanding of the same, and is sufficient to enable such persons to use my invention.

The leading features of my design consist in the representation at A of deers, dogs, trees, and trees. To the branches of the trees are suspended Chinese lanterns. Between the tree and dog a floral plant is shown. At B, C, and E are shown ornamental cross-borders. These, with the plain cross-border D, make an orna-

mental dado for a curtain. At F is shown a portion of the body of the curtain, which represents ornamental inlays in mosaic forms, all as shown in the photographic print, making a part of this specification.

What I claim as my invention, and desire to secure by Letters Patent, is—

The design for a curtain, consisting of the representation at A of deers, dogs, trees, lanterns, and floral plants, in combination with ornamental cross-borders at B C E, plain border D, and ornamental body F, the whole making an ornamental dado and body design for a curtain, as shown and described.

R. PAUL HEMMING.
